United States Patent Office.

ROBERT HITCHCOCK, OF SPRINGFIELD, MASSACHUSETTS, ASSIGNOR TO HIMSELF,
GEORGE C. FISK, AND LEVI O. HANSON, ALL OF SAME PLACE.

Letters Patent No. 74,359, dated February 11, 1868.

IMPROVED LINK-JOINT FOR CAR-SEATS.

The Schedule referred to in these Letters Patent and making part of the same.

TO ALL WHOM IT MAY CONCERN:

Be it known that I, ROBERT HITCHCOCK, of Springfield, Hampden county, Commonwealth of Massachusetts, have invented a new and useful Improved Link-Joint for Car-Seats; and I do hereby declare that the following is a full and exact description thereof, reference being had to the accompanying drawing, and to the letters of reference marked thereon. In the drawings—

Figure 1 represents a side view of my invention applied to a car-seat, and

Figure 2 a detailed view of the same.

This invention consists of a new and simple joint for the link of a car-seat, where it is connected with the back of the seat, serving for the same either way the back is turned.

In construction I form my joint of a piece, A, of malleable iron usually, which may be screwed upon the edge of the car-seat back, as is shown in fig. 1. A socket is formed into this piece, at a convenient part of it, for the end of the link B to be attached in. It is in the peculiar construction of this socket, G, that my invention lies principally, the object of this invention being to make a joint which shall be very strong, and yet not cumbrous.

In most all of the joints now in use there is a twisting strain upon the pin connecting the link with the ear, owing to the pressure of the seat backwards as well as downwards. This is also very much increased at the moment of turning the seat over, when the jar is very apt to break out the pin, which in my device is represented by E. To obviate this, I form my socket, G, so that the downward and outward pressure of the seat does not bring any leverage against the pin E, but relieves the latter, the edges of the end of the link B bearing against the inner edges above, and below, of the socket G. Thus, in fig. 2, it is seen that on each side of the pin E, above and below, the width of the socket is about the same as that of the end of the link. From these two points, however, it tapers each way, so that in front and rear it is much wider than in the centre, where a and a approach towards each other. In this it is also shown that the top back edge, b, of the socket rests upon the top edge of the end of the link, and the front bottom edge of the socket, c, bears against the lower edge of the end of the link, thus taking all strain, except the direct one backwards from the link.

This device can be made much cheaper than the ordinary ones in use, and may be covered up or attached outside to the edge of the car-seat, in the latter case making an ornamental instead of bungling appearance.

Now, having described my invention, what I claim as new, and desire to secure by Letters Patent, is—

A link-joint for car-seats, in which the end of the link B is pinned in a socket, G, the latter having its top and bottom edges tapered each way from a central point in line with the pin E, substantially as is herein shown and described.

ROBERT HITCHCOCK.
